UNITED STATES PATENT OFFICE.

THEODORE A. H. FALZ, OF WILMERDING, PENNSYLVANIA.

DESIGN FOR AN EARTH-AUGER.

SPECIFICATION forming part of Design No: 30,847, dated May 23, 1899.

Application filed April 21, 1899. Serial No. 713,970. Term of patent 14 years.

To all whom it may concern:

Be it known that I, THEODORE A. H. FALZ, a citizen of the United States of America, residing at Wilmerding, in the county of Allegheny and State of Pennsylvania, have invented a certain new and useful Design for an Earth-Auger, of which the following is a specification, reference being had therein to the accompanying drawings.

- This invention relates to a certain new and original design in earth-augers.

In the accompanying drawings, Figure 1 is a side view of my new design for an earth-auger, and Fig. 2 is an underneath plan view of the same.

As shown in the drawings, the essential or material feature of my design consists of the blade A, which in top plan is substantially circular-shaped and in side elevation is hopper-shaped or cone-shaped, having an irreg-

ular cut from its edge to the center, forming an opening B, and one edge of the cone-shaped blade extending beyond the central stem, producing a lip, as at C. The central stem E terminates in the bit F at its lower end and at its upper end in the reduced portion G, having the diverging handles H, extending at right angles thereto.

Having fully described my invention, what I claim as new, and desire to secure by Letters Patent, is—

The design for an earth-auger as herein shown and described.

In testimony whereof I affix my signature in the presence of two witnesses.

THEODORE A. H. FALZ.
